UNITED STATES PATENT OFFICE

HELENE MALNICK, OF CHICAGO, ILLINOIS

BRASSIÈRE

Application filed January 30, 1930. Serial No. 424,593.

This invention relates to brassières.

The objects of the invention include the provision of a brassière that shall be especially suited to effect the proper natural appearance of mothers and other wearers having abnormally large busts; to afford the necessary support for insuring correct bust development of adolescent wearers; to maintain the correct and natural bust posture of normally developed wearers; and to accomplish all of these results with a maximum of comfort and convenience to the wearer in each case.

Other objects and advantages of the invention will appear from a consideration of the following detailed description in conjunction with the accompanying drawing, in which:

Figure 1 is a front view of a brassière embodying the invention, with the side and rear portions thereof laid out in the same plane as the front portions for clarity of illustration but showing, however, the form of the front portions when in place on the wearer;

Fig. 2 is a front view of the garment in place on the wearer;

Fig. 3 is a side view of the same; and

Fig. 4 is a fragmentary front view of a modified form of the invention.

Referring to the drawing, the garment shown in Figs. 1, 2 and 3 comprises two breast-receiving portions or pockets 11, 11, which are made of yielding fabric. Such fabrics are well known and the yielding qualities thereof are produced to the desired degree by the proper selection of materials and methods of weaving. The lower edges of the portions 11, 11 are bordered by a common band or strip 12 of elastic material, such as rubber-reinforced, cloth-covered fabric, and the inner and upper edges of each of these portions are bordered by a strip 13 of similar material. The inner and top edges of the portions 11, 11 are so tucked and fas-

tened to the strip 13 that when the garment is in place on the wearer the strip 13 and the inner edges of the portions 11, 11 first converge upwardly from their bottom edges and then diverge to their highest points, in the angular relation shown. The upper edges are so tucked and fastened that when in place on the wearer they taper downwardly and extend outwardly to points substantially vertically above the respective ends of the bottom strip 12, and the portions 11, 11 terminate along the vertical lines defined by these points.

At their outer edges the portions 11, 11 are securely attached to portions 14, 14, respectively, which are made of firm, unyielding fabric. The upper and lower edges of the portions 14, 14 extend substantially in alignment with the corresponding edges of the portions 11, 11 to a sufficient length to encircle the body of the wearer, and the outer extremities of said portions 14, 14 are provided with suitable fastening means, indicated at 15, 15, such as snap fasteners or the like. These fasteners are adapted to be secured at the back in the usual manner to hold the garment securely around the bust of the wearer.

The two portions 11, 11 are connected at the point of nearest approach of their inner edges to each other, by a nonelastic strip or band 16, which is adapted to be drawn inwardly toward the body of the wearer when the garment is donned, thus effecting separation of the breasts in cases where this will not occur with other types of garments. The provision of the connecting band 16 is an important feature of the present invention, since the fulfillment of its function as described is necessary to the proper appearance of the wearer.

From the uppermost points of the marginal elastic strips 13, 13, shoulder straps 17, 17 extend, and have their opposite extremities threaded through loops or eyelets 90

18, 18, respectively, in the upper edges of the corresponding rear portions 14, 14 of the garment. The free ends of the straps 17, 17 are doubled back and attached to suitable 5 clasps 19, 19, which are adapted to grasp the main portions of the shoulder straps at positions adjusted to the needs and comfort of the individual wearer. The straps 17, 17 may be either integral with the strips 13, 13, 10 or of separate pieces attached to said strips, but in any event are of the same or similar elastic material to provide a comfortable and effective support for the garment. The wearer's comfort is also preferably enhanced 15 by the provision of light, protective pads 20, 20 which are attached to the under sides of the straps 17, 17 at the places of contact with the shoulders.

The garment of modified design shown in 20 Fig. 4 comprises pockets or portions 21, 21 of the same material and for the same purposes as the portions 11, 11 of the first-described embodiment of the invention, but of slightly modified shape in that the lower 25 and inner corners of said portions are somewhat rounded, as shown. Each of these portions 21, 21 is bordered by an elastic strip 22 which replaces both the strips 12 and 13 of the garment shown in Figs. 1, 2 and 3. 30 A short connecting band 23 of non-elastic material is provided between the portions 21, 21 at the point of nearest approach of the inner edges of said portions to each other, and this band functions in the same manner as the band 16, previously described. 35 Shoulder straps 24, 24 are provided in the same relation to the other parts of the garment as the straps 17, 17 of the garment first described, and the other portions of the 40 garment are likewise of design similar to that first set forth.

Another important feature of the invention resides in the shape of the portions 11, 11 and the arrangement and manner of tucking and fastening the same at their inner and top edges to the strips 13. By reason thereof it is possible for the garment to assume the angular positions at the upper and inner portions of the elastic border strips 13, 13 of the garment shown in Figs. 1, 2 and 3. The similar angularity of the corresponding portions of the strips 22, 22 of the garment shown in Fig. 4 is effected by the same arrangement. 50 It is largely by reason of this formation of the garment that the connecting band 16 or 23, as the case may be, is drawn inwardly against the body of the wearer, as previously set forth.

The formation and materials of the garment, as above described, are such that the most advantageous and desirable results are obtained by the wearer. The shape of the portions 11, 11 and the use of yielding fabric therefor in combination with the elastic border strips 12 and 13 cause the breasts of the 60

wearer, particularly in abnormally developed cases, not only to be held firmly in lifted position, but to be forced outwardly toward the arm-pits and to be separated by reason of the previously described action of the band 16 or 23 and the assumption when, in wear, of the angular arrangement of the strips 13, 13 or 22, 22 along the upper and inner edges of the portions 11, 11 or 21, 21. All of these conditions combine to produce the most pleasing appearance and the most natural and comfortable bust posture. For adolescent girls the garment insures correct and natural bust development, and after maturity the proper protection and support are maintained.

While only certain specific embodiments of the invention have been shown and described herein, it will be apparent to those skilled in the art that various changes and modifications other than those disclosed herein may be made in the details of design without departing from the spirit and scope of the invention, as set forth in the appended claims.

What is claimed as new and is desired to secure by Letters Patent, therefore, is:

1. A garment of the kind described, comprising two breast-receiving portions or pockets of yieldable fabric having inner and upper edges diverging upwardly and outwardly from the middle front portion of the garment, elastic strips bordering said portions on the inner and top edges thereof, a single elastic strip bordering the bottom edges of both of said portions and bridging the space between said two portions, and a non-elastic band connecting said portions substantially at the point of nearest approach of said inner edges to each other. 10

2. A garment of the kind described, comprising two breast-receiving portions or pockets of yieldable fabric having inner and upper edges diverging upwardly and outwardly from the middle front portion of the garment, elastic strips bordering said portions on the inner and upper edges thereof, elastic means bordering the bottoms of said pockets and bridging the space therebetween and a non-elastic band connecting said portions substantially at the point of nearest approach of said inner edges to each other, to hold the same in a predetermined spaced relation. 110

3. A garment of the kind described, comprising two breast-receiving portions or pockets of yieldable fabric so shaped that each diverges from the other, a non-elastic band connecting said portions substantially at the point of nearest approach to hold the same in a predetermined spaced relation, and elastic means bordering said portions on their diverging sides. 125

4. A garment of the kind described, comprising two breast-receiving portions or 130

pockets of yieldable fabric so shaped that each diverges from the other, a non-elastic band connecting said portions substantially at the point of nearest approach to hold the same in a predetermined spaced relation, elastic strips bordering said portions on their diverging sides and a band bordering the bottoms of said portions and adapted to bridge the space therebetween and bring the garment into firm contact with the body of the wearer.

In witness whereof, I have hereunto subscribed my name.

HELENE MALNICK.
